UNITED STATES PATENT OFFICE

108,036

DESIGN FOR AN ADVERTISING DEVICE OR THE LIKE

Jean O. Reinecke, Chicago, Ill., assignor to Meta
Dewes Burgweger, Winnetka, Ill.

Application October 7, 1937, Serial No. 72,042

Term of patent 14 years

To all whom it may concern:

Be it known that I, Jean O. Reinecke, a citizen of the United States, residing at Chicago, in the county of Cook and State of Illinois, have invented a new, original, and ornamental Design for an Advertising Device or the like, of which the following is a specification, reference being had to the accompanying drawing, forming part thereof.

In the drawing, Fig. 1 is a perspective view, and Fig. 2 is a top plan view, of an advertising device or the like, illustrating my new design.

I claim:

The ornamental design for an advertising device or the like, as shown.

JEAN O. REINECKE.
